UNITED STATES PATENT OFFICE.

JOSEPH ERRET, OF CLEVELAND, OHIO.

SIDE-BOARD FASTENER.

SPECIFICATION forming part of Letters Patent No. 729,851, dated June 2, 1903.

Application filed January 18, 1902. Serial No. 90,301. (No model.)

To all whom it may concern:

Be it known that I, JOSEPH ERRET, of Cleveland, Cuyahoga county, Ohio, have invented a new and useful Side-Board Fastener, of which the following is a full, clear, and exact description, reference being had to the accompanying drawings, forming part of this specification, in which—

Figure 1 is a front elevation showing my improved fastener in locked position; and Fig. 2 is a central vertical section of the same.

My invention relates to the metallic fasteners employed for drawing and securing together side-boards of wagons, and is designed 15 to provide a cheap and simple device of this character which will give a center-line draft on the parts of the fastening. Heretofore in fastenings of this class one of the parts has been provided with a laterally-projecting 20 hook portion engaged by a cam-lever placed at one side of the center line of the other casting. In such constructions the draft on the parts tends to draw them out of place and does not give desirable results.

25 In my improved fastener the hook upon the one part and the cam upon the other part are in the center line or longitudinal axis of the fastener, giving a direct central draft and improving the action.

30 In the drawings, 2 represents the lower casting or bracket having securing-ears 3, and 4 is the top casting having securing-ears 5. The lower casting is provided with a centrally-located outwardly-projecting lug 6, having an inner groove forming a hook 7. At the base of the lug is a slot through which 35 extends the depending leg 8 of the top cast-

ing. A cam-lever 9 is pivoted to the top casting at 10, its axis being in the longitudinal axis of the top casting, and the cam is provided with a cam-groove 11, which engages the hook upon the lower casting and draws the board into engagement. A stop-pin 12 limits the unlocking or releasing movement of the cam-lever and prevents its dropping 45 down in contact with the lower board.

The advantages of my invention result from the new location of the interacting hook and cam, which give a direct central pull and improve the action and also the appearance of 50 the fastener.

Variations may be made in the form of the parts without departing from my invention.

I claim—

In a side-board fastener, a lower casting having an outwardly-projecting lug with an inner hook and a slot extending through the casting from back to front below said hook, and an upper casting having a lever pivoted in its longitudinal axis and arranged to swing 60 in a plane parallel to the plane of the side-boards and provided with a cam-surface engaging the inner hook on the lower casting and with a depending leg entering the said slot and engaging the lower casting, the said 65 slot and said leg being arranged in a line with the pivot of the lever, substantially as described.

In testimony whereof I have hereunto set my hand.

JOSEPH ERRET.
